ABSTRACT OF THE DISCLOSURE

Ammonium phosphate solutions thickened with galactomannan gum are stabilized with respect to viscosity by the addition of a minor amount of a heavy metal ion such as Co^{++} , Cu^{++} , or Mn^{++} .

BACKGROUND OF THE INVENTION

This invention relates to viscosity stabilized ammonium phosphate solutions which are used extensively in the field of fighting fires, particularly forest fires.

It is well known to thicken ammonium phosphate solutions with small amounts of galactomannan gum to improve its air drop patterns and its ability to stick to surfaces, e.g., trees and bushes with which they come into contact. See, for instance, U.S. Pat. 3,223,649 granted Dec. 14, 1965. So as to be ready at a moment's notice, these thickened ammonium phosphate solutions are made up in advance. However, these solutions on prolonged standing often show a serious loss in viscosity. Various stabilizers have been proposed, e.g., sodium sulfite, zinc sulfite, sodium thiosulfate, see U.S. Pat. 3,146,200, but the amount required is impractical.

Therefore it is an object of this invention to provide ammonium phosphate solutions having improved viscosity stability upon prolonged standing.

It is a further object to provide improved viscosity solutions with minimal amounts of stabilizers.

Other similar objects of the invention will become apparent to those skilled in the art as the invention is further described below.

SUMMARY OF THE INVENTION

The viscosity stability of an ammonium phosphate solution thickened with a galactomannan material is improved by the addition of a minor, but stabilizing, amount of a transition, i.e., heavy, metal ion.

DESCRIPTION OF THE PREFERRED EMBODIMENTS

The ammonium phosphate solutions in which these transition metal ions perform particularly effectively are those that contain at least about 0.5 weight percent, and up to the level at about which the solutions are saturated therewith, of dissolved ammonium phosphate salts, including monoammonium orthophosphate and/or diammonium orthophosphate salts, and also including the diammonium and monoammonium mixed orthophosphate salts that also contain an alkali metal cation, such as monoammonium disodium orthophosphate, monoammonium dipotassium orthophosphate and the like, no matter from what source these materials were derived, or in what form the materials are initially introduced into the aqueous compositions. Generally, it is preferred that the inhibited aqueous phosphate solutions of this invention have a pH between about 3 and about 9. When monoammonium orthophosphate is the only ammonium phosphate salt present in the inhibited fire-control compositions of this invention, the preferred pH of these compositions is generally from about 3 to about 5. Similarly, when diammonium orthophosphate is the only ammonium phosphate

2

salt contained therein, the preferred pH is from about 7 to 9. When mixtures of monoammonium orthophosphate and diammonium orthophosphate are utilized, pH's between these preferred ranges are generally more desirable. However, compositions having pH's somewhat higher or lower than these preferred ranges can also be utilized to advantage in the practice of the present invention.

The galactomannan materials to which this invention relates are polysaccharides, generally termed hemicelluloses, and are long chain polymers of galactose and mannose units. While their exact composition is not known, they have been found to yield these two sugars on hydrolysis. They are gum-like materials, generally found in plant seeds. Examples of the galactomannans are guar gum, obtained from *Cyamopsis tetragonolobus* (a legume); locust bean gum, obtained from *Ceratonia siliqua*; and tara gum, obtained from *Cesalpinia spinosa*. These materials typically comprise about 5 to 15% by dry weight of the ammonium phosphate composition.

The viscosity stabilized ammonium phosphate solutions of the present invention can also contain other materials (compounds) without detracting substantially from the benefits that can be obtained by practicing this invention, for example, the solutions can contain minor amounts of surfactants; inorganic and organic complexing agents such as the alkali metal tripolyphosphates, pyrophosphates and trimetaphosphates, as well as the higher polyphosphates such as the hexametaphosphates and also can contain ethylenediamine tetraacetic acid and various alkali metal and ammonium salts thereof and the alkali metal and ammonium nitrilotriacetates; corrosion-inhibiting ingredients; and organic and inorganic pigments and dyes; as well as many other materials.

The viscosity stabilizers of this invention are the transition or heavy metal ions of the fourth and fifth order of the Periodic Table such as various zinc, copper, nickel, cobalt, manganese, chromium and cadmium ions. More preferred are the metal ions from the fourth order especially those having an atomic number below 30 and particularly preferred are the ions of metals having odd atomic numbers from 25 to 29 inclusively. These ions are added to the ammonium phosphate solution in an amount from about 10 to 70 parts per million (p.p.m.) and preferably from about 15 to 65 p.p.m. (This phenomenon is somewhat surprising since these ions in the foregoing amounts are known to have the reverse effect in other thickeners such as carboxymethylcellulose which has also been employed as a thickener for ammonium phosphate solutions.) The metal ions are conveniently added to the ammonium phosphate composition as a water soluble compound having an anion compatible with the composition, e.g., a chloride or sulfate.

The inhibited phosphate compositions of this invention can be manufactured via any of a number of manipulative methods, without any noticeably detrimental effects upon the ultimate performance of the compositions. For example, the sulfate compound can simply be dissolved by intermixing it into or with the otherwise completely formulated aqueous compositions, or at any other stage during the preparation of the fire-control composition. Via another method, the sulfate compound can first be dissolved in water and the resulting solution then intermixed subsequently with the ammonium phosphate materials.

Still another process for manufacturing the aqueous stabilized phosphate compositions described heretofore involves one of the preferred embodiments of the present invention. This preferred embodiment comprises a "concentrate" mixture of one or more of the ammonium phosphate salts described heretofore with one or more of the stabilizer compounds, generally in a particulated,

solid form. Preferably the compound(s) and ammonium phosphate salt(s) will be present in this concentrate composition or mixture in amounts proportionate to those found in the fire-control compositions described heretofore, so that the final fire-control composition can be manufactured by simply dissolving the concentrate in a sufficient amount of water. In other words, generally the preferred concentrate compositions of this invention will contain at least one of the above-described ammonium phosphate salts, a galactomannan gum and at least one of the stabilizer compounds in a weight range, respectively, of from about 50.0 to 93.0 percent by weight, 5 to 15.0% and 0.05 to 1.50% with the balance being optional materials listed below. It is still further preferred that these particulated, solid concentrate compositions contain a total of at least about 50 weight percent of one or more of the above-described ammonium phosphate salts. These preferred concentrate compositions can also contain effective amounts of practically any other

ous air-drops of fire-control compositions, very little weighing and handling equipment is available that is capable of manufacturing the fire-control compositions from the individual components.

The following examples are included to illustrate the present invention but are not to be considered as limiting. Unless otherwise specified all parts are by weight.

EXAMPLE 1

A commercial aqueous ammonium phosphate solution containing a guar gum type thickener (0.9%) was prepared with varying amounts of copper as the viscosity stabilizer. The copper was added as copper sulfate. The solutions were maintained at room temperature (approximately 74° F.). The viscosity was determined with a Brookfield viscometer equipped with a No. 3 spindle rotating at a speed of 60 r.p.m. The results are tabulated in Table I which follows:

TABLE I.—VISCOSITY OF AMMONIUM PHOSPHATE SOLUTIONS CONTAINING COPPER (II) AS A FUNCTION OF STORAGE TIME

ngredients desired in the final fire-control compositions, e.g., dyes, pigments, water-softening agents and the like, all of which should preferably be present in the concentrate compositions in minor amounts, as compared to the ammonium phosphate salt(s) contained therein. Some of the advantages of these preferred concentrate compositions can readily be appreciated when it is realized that at 45 most points from which aircraft are loaded for their vari-

EXAMPLE 2

An ammonium phosphate fire-control formulation containing a guar gum type thickener (0.9%) was dissolved in water containing varying amounts of copper, zinc or cadmium as the viscosity stabilizer. The metal ion was added as the chloride salt. Test conditions of Example 1 were used. The results are tabulated in Table II and Table III below.

¹ Metal ion concentration on a total solution basis.

From the foregoing it will be seen that the degree of viscosity stabilization can be tailored to fit the particular requirement by choice of metal ion with due allowance for the nature of the galactomannan gum.

The foregoing examples have been described for the purpose of illustration and not limitation. Many other modifications and ramifications will naturally suggest themselves to those skilled in the art based on this disclosure. These are intended to be comprehended as within the scope of this invention.

The embodiments of the invention in which an exclusive property or privilege is claimed are defined as follows:

1. An ammonium phosphate solution containing (1) at least 0.5 weight percent of ammonium phosphate, (2) as a thickening agent a galactomannan gum in an amount of from about 5 to 15 weight percent, based on the dry weight of said ammonium phosphate and (3) as a viscosity stabilizer a transition metal salt selected from the group consisting of cobalt chloride, cobalt sulfate, copper chloride, copper sulfate, manganese chloride, manganese sulfate, chromium sulfate, chromium chloride, nickel chloride, nickel sulfate, cadmium chloride and cadmium sulfate, said salt being present in an amount to provide from about 10 to about 70 p.p.m. of metal ions.

2. The composition of claim 1 wherein the transition metal salt is cuprous chloride, cuprous sulfate, manganous sulfate, manganous chloride, cobaltus chloride or cobaltus sulfate.

3. A concentrated ammonium phosphate composition

useful when diluted and dissolved in water, said composition comprising at least one ammonium orthophosphate salt, a galactomannan gum and a transition metal salt selected from the group consisting of copper chloride, copper sulfate, manganese chloride, manganese sulfate, cobalt chloride, cobalt sulfate, chromium sulfate, chromium chloride, nickel sulfate, nickel chloride, cadmium chloride and cadmium sulfate, said respective weight percents being from about 50.0 to about 93.0; about 5 to about 15 and about 0.05 to about 1.5.

4. The composition of claim 3 wherein the transition metal salt is cuprous chloride, cuprous sulfate, cobaltus chloride, cobaltus sulfate, manganous sulfate or manganous chloride.
